UNITED STATES PATENT OFFICE.

MARK N. PUTNAM, OF LOS ANGELES, CALIFORNIA.

HYDROCARBON-GAS-PRODUCING BURNER.

1,289,910.

Specification of Letters Patent. Patented Dec. 31, 1918.

Application filed March 25, 1918. Serial No. 224,627.

To all whom it may concern:

Be it known that I, MARK N. PUTNAM, a citizen of the United States, residing at Los Angeles, in the county of Los Angeles and State of California, have invented new and useful Improvements in Hydrocarbon-Gas-Producing Burners, of which the following is a specification.

My object is to make an improved hydrocarbon gas producing burner, especially for domestic use, and my invention consists in the novel features herein shown, described and claimed.

Figure 1 is a perspective showing my gas producing burner in a hot plate, embodying the principles of my invention, mounted upon a table, there being two burners and the grates being removed and the oil supply tank being connected to the burner, the generator being over one burner and not over the other.

Fig. 2 is an enlarged vertical longitudinal sectional detail on the line 2-2 of Fig. 1.

Fig. 3 is an enlarged fragmentary cross section on the lines 3-3 of Figs. 1 and 2.

Fig. 4 is an enlarged fragmentary sectional detail of the generator and generator nozzle on the same plane as Fig. 2.

Fig. 5 is a perspective of a modified form 30 of burner intended for use in a gas range, parts of the oven being broken away.

The hot plate frame 1 may be of the ordinary construction used in making gas hot plates, and this frame is adapted to rest upon a flat support such as a table 2. The openings 3 and 4 in the frame 1 are to receive the grates for supporting the cooking utensils, and the burner caps 5 and 6 are mounted under the centers of the openings 3 and 4 to discharge upwardly through the grates. The burner cap 5 is an annular concavo-convex plate having radial slits 7 for the discharge of the gas, and having a vertical central air passage 8. The cap thus constructed is mounted upon a base having an annular rim 9, a dished web 10 extending inwardly and downwardly from the rim, a hub 11, at the center of the web and having an opening through which the shank 12 is inserted, said shank 12 extending downwardly from the cap 5 around the opening 8. The mixing tube 13 extends from the base and discharges into the chamber 14 through a throat 15. A baffle 16 is formed by taking a strip of sheet metal, forming perforations 17 in the strip and bending the strip to form a U-shaped loop and inserting the ends of the loop into the throat 15, said baffles serving to break up the force of the fuel mixture coming through the mixing tube 13 to the chamber 14. An extension 18 of the mixing tube extends toward the burner cap 6 and is connected to a globe valve 19 and the second mixing tube 20 connects the globe valve 19 to the burner base 21 supporting the cap 6. The intake arm of the mixing tube extends upwardly from the mixing tube 13 half way between the two burners and comprises the vertical portion 22, the elbow portion 23 and the horizontal portion 24, said horizontal portion 24 being directly above the main mixing tube 13. A gas nozzle 25 is mounted parallel with the mixing tube 13 some distance above the level of the cap 5. The air pipes 26 and 27 are formed integral with the intake end of the intake portion 24 and extend horizontally cross wise like a T, the outer ends of the air pipes being turned downwardly and the nozzle 25 being inserted through the wall at the junction of the air pipes so as to discharge centrally through the portion 24. An opening is formed through the casting just in front of and above the discharge end of the nozzle 25, said opening being provided with a removable cover 28. The generating pipe 29 is screwed into the nozzle 25 and extends in a horizontal plane diametrically across the burner cap 5 some distance above the cap, the cold end of the generator pipe 29 being supported by a bracket 30 secured to the frame 1. A sleeve 31 is inserted tightly into the discharge end of the generator pipe 29. A disk 32 is mounted in the generator pipe against the inner end of the sleeve 31, said disk being preferably formed of 100 mesh woven copper wire, thus leaving a gas chamber 33 between the disk 32 and the orifice 34 in the nozzle 25. A section 35 of granular material, such as carborundum crystals, copper or brass lathe turnings or the like, is placed in the generator tube 29 against the disk 32 and a second disk 36 is placed against this section of granular material. A second section 37 of granular material is placed against the disk 36 and so on until the generator pipe 29 is filled to the desired extent. A union 38 is mounted upon the cold end of the generator pipe 29. The oil feed pipe 39 is connected to the union and connected to the oil supply tank.

40. A pressure gage 41 is mounted upon the tank 40 and the tank is supplied with compressed air by pump 42. The oil pipe 39 leads through a regulating valve 43 mounted 5 upon the front side of the frame 1 and then to the union 38 so that the generator may be controlled from the front of the table 2. The stem of the globe valve 19 leads to the front of the frame 1 and is controlled by a 10 handle 44.

In the practical operation of the hot plates or gas ranges, a torch of asbestos or the like is saturated with wood alcohol and placed under the generating pipe 29 until the pipe 15 is sufficiently heated. Then the valve 43 is opened and oil flows into the end of the generator pipe 29 and through the packing and is converted into hot hydrocarbon gas. The hot hydrocarbon gas is discharged 20 through the nozzle 34 and draws in fresh air through the pipes 26 and 27 and the mixture flows through the portion 24, the elbow 23 of the portion 22 to the mixing tube 13 and through the throat 15, through the baffle 25 16 into the chamber 14 and finally passes through the slits 7 and burns above the cap 5 under the generating pipe 29, thereby keeping the generating pipe hot, and the operation continues as long as desired. 30 When the other burner is to be used, the globe valve 19 is opened and gas passes through the extension 18, through the globe valve and through the tube 20 to the cap 6.

In the modification shown in Fig. 5, the 35 air pipes 45 and 46 are connected to the intake end of the mixing tube 47, said mixing tube 47 leading to a long burner 48 and the generating pipe 49 is mounted directly over this long burner 48 and a branch pipe 50 of 40 the mixing tube leads through the globe valve 51 to the burner 52, said burner 52 being parallel with the burner 48 so by closing the valve 51, the burner 48 may be operated and the operation of the burner 48 45 serves to keep the generating pipe 49 hot, and so that by opening the valve 51, the burner 52 may be lighted without generation, the same as artificial or natural gas. When the pressure in the tank 40 is properly 50 regulated and the valve 42 properly manipulated, a pure hydrocarbon gas is formed in the generator 29, from oil such as kerosene or coal oil, and the passage of this hydrocarbon gas through the orifice 34 to the 55 burner caps, together with the intake of fresh air through the pipes 26 and 27, produces a perfect fuel mixture, and produces perfect combustion above the burner caps distinguished by a turquois greenish blue 60 flame free from yellow, white or red tips and giving off no poisonous gases, or odors, no smoke, soot or carbon.

Any reasonable number of burners may be supplied from one generator, and the burners 65 may be used either in open flame mount-

ings or in closed mountings, such as ovens, water heaters, gas logs and gas grates or gas mantles for fire plates, coffee and hot water urns, cook stoves and the like. No stove pipe or flue connection is necessary 70 for hot plates, gas ranges, gas stoves and the like.

After the generating burner has been started, the other burners may be turned on or off at will, the same as in the gas 75 construction. The generator pipe 29 is preferably made of good brass or copper tubing, and the oil pipe 39 is preferably wire tubing.

I claim:

1. A hydrocarbon gas producing burner, 80 comprising a packed generating pipe, a nozzle mounted upon one end of the generating pipe, means for feeding oil to the other end of the generating pipe, air inlet pipes mounted horizontally with their open ends extending downwardly, the nozzle extending through the wall at the junction of the air inlet pipes, a fuel mixture pipe leading from the air inlet pipes in line with the nozzle and downwardly and backwardly, and a 85 burner cap and base connected to the end of the fuel mixture pipe, said burner cap being located directly below the generating pipe.

2. In a hydrocarbon gas producing burner, 90 a straight generating pipe, a nozzle upon one end of the generating pipe, a sleeve within the nozzle end of the generating pipe, a 95 gauze in the generating pipe against the sleeve, packing in the generating pipe 100 against the gauze, a second gauze in the generating pipe against the packing, and a second packing in the generating pipe against the second gauze, the same being continued throughout the length of the generator. 105

3. In a hydrocarbon gas producing burner, 110 a burner base, a burner cap mounted upon the burner base, a mixing tube discharging into the burner base through a throat, a baffle in the throat, a generating pipe mounted above the burner cap, a nozzle upon the generating pipe, an air intake pipe into which the nozzle discharges, and a mixing tube portion leading from the nozzle to the 115 main mixing tube.

4. A hydro-carbon gas producing burner, 120 comprising a packed generating pipe, a nozzle mounted upon one end of the generating pipe, means for feeding oil to the other end of the generating pipe, air inlet pipes mounted horizontally with their open ends extending downwardly, the nozzle extending through the wall at the junction of the air inlet pipes, a fuel mixture pipe leading from the air inlet pipes in line with the nozzle and 125 downwardly and backwardly, a burner cap and base connected to the end of the fuel mixture pipe, said burner cap being located directly below the generating pipe, a second burner cap and base connected to the fuel 130

mixture pipe, and a valve for controlling the second burner cap and base.

5. In a hydro-carbon burner, a generating pipe, a nozzle mounted upon one end of the generating pipe, air inlet pipes mounted horizontally with their open ends extending downwardly, the nozzle extending through the wall at the junction of the air inlet pipes, a fuel mixture pipe leading from the air inlet pipes in line with the nozzle and down-

wardly and backwardly, a burner connected to the fuel mixture pipe under the generating pipe, and a second burner connected to the fuel mixture pipe, there being a valve in the fuel passage for controlling the second burner independent of the first burner.

In testimony whereof I have signed my name to this specification.

MARK N. PUTNAM.
